UNITED STATES PATENT OFFICE.

D FRANKLIN PYLE, OF WASHINGTON, DISTRICT OF COLUMBIA, AND JAMES ANDERSON,
OF CATONSVILLE, MARYLAND.

APPARATUS FOR MAKING SPARK PLUGS.

Application filed October 27, 1921. Serial No. 510,754.

To all whom it may concern:

Be it known that D FRANKLIN PYLE and JAMES ANDERSON, citizens of the United States, residing at Washington, District of Columbia, and Catonsville, State of Maryland, respectively, have invented certain new and useful Improvements in Apparatus for Making Spark Plugs, of which the following is a specification.

10 This invention relates to an apparatus for manufacturing spark plugs.

The spark plug for which the apparatus is designed to manufacture is one comprising a metallic shell threaded in the usual manner for insertion into the wall of the explosion chamber of explosive engines, and in which there is a core of insulating material such as glass, in which there is embedded in its completed form, the positive pole or electrode.

In the manufacture of spark plugs of this character, it is essential that the shell of the plug be rigidly and positively supported at certain stages in the operations incident to its manufacture, as to both lateral and vertical movement, it being desirable to prevent lateral movement so that the electrode or the parts forming the central pole or electrode be accurately centered in the insulating material within the shell, and also in relation to the outer extremities of the shell itself, and held positively against vertical movement so that the die carrying plunger, which forms an essential part of the apparatus, will not lift the plug from its seat when said plunger recedes after having compressed the insulating material into the shell and inserted therein the central pole or electrode or a part thereof.

The object of the invention is to improve the construction of machines or molds of this character generally, and particularly to provide a construction wherein the metallic shell of the plug is braced and held rigidly in proper position in the mold during the operations of filling said shell with insulating material, and embedding in such material the electrode, and to provide a novel and efficient means for holding the shell and its contained insulator and electrode in firm and positive position in the mold upon the recession of the die carrying plunger.

A further object of the invention is to provide a construction wherein the plug is readily and conveniently ejected from the base of the mold.

Other objects and advantages of the invention will, in the course of the following description, become apparent to those skilled in the art to which this invention appertains, and the points of novelty will be set forth in the claims.

In carrying out the invention we provide a table or rest for the mold which contains parts which cooperate with the mold during the various operations incident to the manufacture of the plug, and may accordingly form particular elements in the combinations of mechanisms about to be described.

In the drawings illustrating the invention:

Fig. 1 is an edge diagrammatic view of a table which may be employed.

Fig. 2 is a plan view, diagrammatic, of a portion of the table.

Fig. 3 is a central section of the lower part of the mold, there being in place in the mold, in section, the shell of a spark plug, and before the same has been filled with molten insulating material.

Fig. 4 is a similar section of a portion of the lower part of the mold in proper relative position to a fragment of the lower end of the plunger, which is also in section, there being also shown in place in the mold, the shell of the plug showing the same filled with insulating material, but before fusing pressure has been applied.

Fig. 5 is a central section of the mold showing in proper relation thereto the plunger, and the means for holding the shell in place during the upward movement of the plunger, there being shown a completed plug in its proper relative position to the mold and plunger parts, the positions of said parts being those which they occupy just before the plunger and die carried thereby recede, or are withdrawn.

Fig. 6 is a top plan view of the upper portion of the ejector.

Fig. 7 is a group view, side elevation and bottom section, of the gripper for initially holding the central electrode in the end of the plunger.

Fig. 8 is a central sectional view of the mold, and a portion of the table upon which it is operated, the section of the table being taken on that point where is located one of the elements of the ejector.

Fig. 9 is a top plan view of the mold.

Referring to the drawings, the numeral 1 designates the table upon which the mold may be operated, of which, and the parts 10 carried thereby, or more intimately associated therewith, more will be said presently.

The numeral 2 designates the base of the mold, as a whole, which base comprises a central portion of substantial build, but for 15 purposes of lightness and ease of handling, the remaining part of the base is of comparatively light construction. It is provided with a bottom flange 2' of considerable width, and at its rear end there is a standard 20 and 3 provided with an opening 4 for the passage of a bolt 5 which extends through ears 5' of a comparatively heavy lid 6, whereby the lid is pivotally secured to the standard so that the same may be brought 25 to horizontal position, or raised out of the way and tilted back as shown in dotted lines in Fig. 5, and in full lines in Fig. 8. The lid is provided with a heel 7 which engages the shoulder 8 on the standard to prevent 30 the lid from moving too far back when lifted. The lid is further provided centrally with an aperture 9 formed with bevelled inner periphery 10 to receive the die carried by the plunger, and an oppositely 35 bevelled lower portion 11, which receives and conforms to the upper edge 12 of the spark plug shell 13. The shell of the plug, as is usual, is provided with the shoulder 14, and for engagement with this shoulder 40 we provide an annular seat 15 which is secured by means of screws 16 to the upper ends of circularly arranged posts 17, the lower ends of the posts being rigidly secured by short screws 18 to the disk 19, fitted and 45 adapted for vertical movement in circular recess 20 made in the bottom of the mold.

The annular seat 15 surrounds a cylindrical pocket 21 into which the lower threaded portion of the shell 13 extends, in position 50 to receive the upper end of the cavity-forming die 22, which die for a portion of its length is threaded as indicated at 23, and is provided with a knifed head 24, by which it may be adjusted vertically for the purpose 55 of forming a cavity of greater or less depth in the molten material when it is poured into the shell, it being obvious that there is sufficient space within the recess 20 for such vertical adjustments, without interfering in any 60 appreciable way with the proper ejection of the finished plug.

Seated in a bore 24' in a boss 25 on the front of the base of the mold is the inner end of handle 26 which is held in place by 65 set screw 27, the outer end of the handle

being provided with a suitable grip portion by which the whole machine may be readily moved from place to place upon the table 1, or any other suitable support.

The numeral 28 designates so much of a standard of a press as is necessary to show its relation to the mold, in one of the stages of the operations incident to making the plug. This standard is provided with a guide groove 29 in which works the plunger 30, held 75 in the groove and guided by a bracket 31 bolted to the standard, as shown; and in an extension 32 of the bracket is a stop 33, whose lower end is adapted to engage the upper surface of the lid 6 to hold the same 80 in proper position upon the upper edge of the shell of the spark plug in the molding operation, and to prevent upward movement of the plug when the plunger recedes, or is being withdrawn. The lower end of the plunger 30 is provided with a threaded recess 34 which receives the threaded boss 35 of the die 36, which die is formed with a centrally circular boss 37 designed to form the depression 38 in the top of the glass insulating material 39 within the shell of the spark plug, the outer edge of the bottom of the die extending in its lowest position to the bottom part of the bevelled portion 10 of the lid, as shown, and to the upper edge 95 of the bevelled portion 16 of the lid, and the die is undercut as indicated at 40, thus forming an annular space when the die is down to receive any very small particles of the insulating material that may, under pressure, during the operation of the molding; be in excess of that necessary to sufficiently fill the shell. The die 36 is provided with a bore 41 which receives the gripper 42 which is formed with a head 43, which fits snugly in the top of the recess 34, and is held therein by the boss of the die, as shown. This gripper is provided with a plurality of resilient fingers 44 designed to grip and hold temporarily, the upper portion of the central electrode *a*, which pole or electrode is bifurcated at its lower end as indicated at *b* for the reception and final retention of the reduced end *c* of the central electrode. 105

Referring particularly to Fig. 8, the numeral 45 designates a lever whose end terminates shortly beyond the edge of the table in a handle 46, and the opposite end of the lever is pivoted at 47 between two ears 48 integral with the table. Preferably about midway of its width, the table is provided with a cylindrical aperture 49 through which extends the lower member 50 of the ejector, which member is provided at its upper end with a broadened portion 51, which engages centrally the under face of the disk 19, the table being recessed as indicated at 52 to receive the head 51 when the member 50 is in its down or lowest position. The 110 115 120 125 130

lower end of the member 50 is pivoted as indicated at 53 to the lever so that a manipulation of the lever will cause the disk 19 and parts carried thereby to be raised at 5 will to the position shown in Fig. 8 for the purpose of ejecting or knocking off the completed plug.

Reverting to the table illustrated in the diagrammatic views Figures 1 and 2, the 10 letter *e* designates a plurality of stops which cooperate with stops *f*, the stops being grouped together at intervals on the table; the front stops *e* serve to limit the forward movement of the mold when the same is 15 pulled within the stops, and the rear stops are provided with flanges, as shown, which slightly overlap the flange 2', the latter stops preventing the lateral movement of the mold from any of its predetermined positions on 20 the table.

The operation of the apparatus above described is as follows:

The lid 6 is thrown back out of the way, and the shell 13, after having been previously heated, is inserted in the pocket 21 in the base of the mold, with the annular shoulder 14 resting upon the inner upper edges of annular seat 15, with the upper part of the cavity-forming die extending into 30 the shell, as shown in Fig. 3. There is inserted in the recess in the cavity-forming die, the reduced lower portion *c* of the central electrode, which portion is, it will be understood, temporarily held in this portion 35 of the die preparatory to its union with the upper portion of the electrode *a*. The lid 6 which is quite heavy, is then brought down on the upper edge of the shell, which by reason of the conforming bevelled surfaces 40 of the lower part of the aperture 9 centers the shell properly upon its rest. The upper part of the electrode *a* is then inserted into the gripper in the die 36, wherein it is firmly, but temporarily held, the electrode 45 having, like the shell and the lower part *c* of the electrode, been previously heated to a degree sufficient to bring about a very tight union, between the upper and lower parts of the electrode, and a fusing of the molten insulating material upon the exposed parts of 50 said electrode. The mold is then moved upon the table to a position under a suitable filler, (not shown) from the nozzle of which is poured into the shell, the glass or 55 other molten insulating material. After the shell receives an adequate amount of material, the mold is moved to the position determined by the appropriate stops, wherein it may be directly below the die of the 60 plunger 30, and upon depression of the plunger, the die will enter the recess in the lid 6 and apply the necessary pressure to the molten material, and depress or form in said material, the proper pre-determined 65 configurations, in the present case, the de-

pression 38, which depression forms the seat in which the lower end of the insulating sleeve rests in the finishing of the plug. This downward movement of the plunger inserts the upper part of the electrode *a*, centrally in the molten material within the shell, and the upper and lower parts of the electrode being in perfect alignment, the lower part will be received between the slightly bevelled bifurcated ends of the upper part, as shown best in Figures 5 and 8. After the glass or other insulating material in the shell has hardened sufficiently, the plunger 30 is raised withdrawing the die from the aperture 9 in the lid 6, and in the withdrawing movement shedding the electrode *a* which remains embedded in the insulating material in the shell, and in the upward movement of the plunger the stop 33 in engagement with the lid 6 steadies and 70 holds the shell, and its then contained parts, against the tendency to follow the plunger.

The mold is then moved to another point on the table pre-determined by the appropriate stops, and this last point is the one 75 immediately above the ejector member 50, so that when the handle to which the member is pivoted is raised, it will lift the disk 19 and parts carried thereby, including the annular seat 15 upon which rests the shell 13, and in the upward movement the shell strips the cavity-forming die from the lower portion of the electrode (see Fig. 8), so that the plug may be readily removed for 80 the final necessary treatments, which in most cases, comprehends the provision of an insulating sleeve for encasing the upper part of the electrode, and the provision of clamp screws, washers, etc. for the convenient 85 reception of the usual electrical terminals.

We do not desire it to be understood as limiting ourselves to the use of any particular kind of press or machine for actuating the upper die, and it is obvious that we may use any suitable machine for this purpose, it only being essential that there be a plunger which carries the die we have described, and the reciprocatory movement or stroke of the plunger may be given to it by any suitable means, as for instance, a hand lever, or by mechanically or electrically operated device, nor do we desire to limit ourselves to the particular form of table shown and described, and may vary the same within the spirit of the invention so long as there are 90 present the elements of certainty and accuracy of the stoppage points for the performance of any of the steps incident to the operation of the machine.

Claims:

1. A mold of the character described comprising a base, an ejector movable vertically therein and comprising in part an annular seat for the article to be filled, a lid having an aperture therein, said lid adapted to rest 95

upon and hold in place said article, and said aperture serving for the passage of the material to be filled into the article, and also as an entrance opening for a suitable plunger, a pressure applying plunger adapted to apply pressure to the material with which the article is filled, and means for actuating said plunger.

2. A mold comprising a base, an ejector 10 in said base, comprising a plurality of posts whose upper ends are connected by an annulus which forms a seat for the article upon which the mold is adapted to operate, means connecting the lower ends of said 15 posts whereby they, and the parts carried thereby, are moved vertically, a lid pivoted upon the base and having an aperture therein for the passage of the material to be filled into the article, and also for the entry of 20 a pressure applying plunger, a pressure applying plunger and means for actuating the same.

3. A mold comprising a base, an ejector in said base formed in part of an annulus 25 forming a seat for the article upon which the mold is adapted to operate, a cavity-forming die within the ejector for the purpose set forth, a lid pivoted above the seat and having an aperture therein for the passage 30 of the material to be filled into the article, and also for the entry of the plunger for applying pressure to the filler of said article, said lid being adapted to prevent movement of the article both vertically and 35 laterally.

4. A mold comprising a body having a flange around its lower edge adapted to cooperate with suitable stops upon a suitable support to hold the mold in a definite pre- 40 determined position, an ejector in said mold comprising in part an annular seat for the article upon which the mold is adapted to operate, a cavity-forming die within the annular seat, a lid above said seat adapted 45 to rest upon the article to simultaneously prevent its movement in vertical or lateral direction, said lid having an aperture therein

for the passage of the filler of the article, and also for the entry of a pressure applying plunger that operates upon the filler, 50 means for actuating the plunger, and means for actuating the ejector for the purposes set forth.

5. A mold comprising a base having a seat for the article upon which the mold is adapted to operate, a lid above the seat and engaging the article to prevent either vertical or lateral movement of said article, said lid having an aperture therein whose sides are inwardly bevelled, a plunger, a die carried 60 by said plunger, the plunger being provided with an undercut annular portion, which when the die is in the aperture in the lid forms an annular pocket for the overflow of excessive portions for the filler, and means 65 for actuating said plunger.

6. In a mold of the character described, in combination, a suitable table having suitable stops thereon which predetermine the positions of the mold on said table, an ejector 70 element carried by said table, a mold comprising a base, an ejector in said base adapted to cooperate with the ejector element of the table, said last mentioned ejector element comprising in part a seat for the article 75 upon which the mold is adapted to operate, a lid having an aperture therein, said lid being adapted to rest upon said article to keep it upon its seat, and to prevent its lateral movement with relation to said lid, 80 and said aperture serving as an entrance for the material to be filled into the article, and also for the entry of a die carrying plunger adapted to exert pressure upon the filler of said article in the molding operation, 85 and means for operating said plunger.

In testimony whereof we affix our signatures in presence of two witnesses.

D FRANKLIN PYLE.
JAMES ANDERSON.
